UNITED STATES PATENT OFFICE.

ALFRED JOHNSON, OF SHEVLIN, MINNESOTA.

WIRE-STRETCHER.

1,303,067.

Specification of Letters Patent.

Patented May 6, 1919.

Application filed May 16, 1917. Serial No. 169,015.

To all whom it may concern:

Be it known that I, ALFRED JOHNSON, a citizen of the United States, residing at Shevlin, in the county of Clearwater and

5 State of Minnesota, have invented certain new and useful Improvements in Wire-Stretchers; and I do hereby declare the following to be a full, clear, and exact description of the invention, such as will enable 10 others skilled in the art to which it appertains to make and use the same.

This invention relates to improvements in wire stretchers.

The object of this invention is to provide 15 a device, which is used to stretch all kinds of wires for wire fences at different times, preparatory to stapling said wires to a post.

A further object of this invention is to provide a supporting member, which is 20 adapted to be embedded in the ground at a spaced distance to the end post, upon which the fence wire is adapted to be secured, means extending from the stretching post and engaging the wires to be secured to the 25 fence post so as to stretch them preparatory to stapling them to the post.

A still further object of this invention is to provide a stretching post, which has a 30 slidable block, which carries a shaft to which is attached a wire clamping means, which is adapted to have the strands of wire secured thereto so that they may be effectively stretched prior to stapling them to the post.

A still further object of this invention is 35 to provide a stretching member having a sliding block carrying a shaft, means for holding the bearing block adjusted on the stretching post, braces pivotally secured to the stretching post and to the end posts 40 upon which the wire is adapted to be secured, thus rigidly supporting the stretching post in spaced relation with the fence post.

A still further object of this invention is 45 to provide a device of this character, which will be simple, practical and comparatively inexpensive in construction, and one that can be manufactured and sold at a low cost.

With these and other objects in view, the invention consists in the novel combination

and arrangement of parts as will be herein- 50 after more fully described and set forth in the claim hereto appended.

In the drawings:

Figure 1 is a side elevation of my improved wire stretcher as assembled and 55 ready for use,

Fig. 2 is a top plan view of the same,

Fig. 3 is a transverse sectional view taken on the line 3—3 of Fig. 1,

Fig. 4 is a top plan view of the stretching 60 post in section, illustrating one of the bracing rods,

Fig. 5 is a perspective view of the stretching member,

Fig. 6 is a fragmentary longitudinal sec- 65 tional view illustrating the manner in which the bearing block is held adjusted within the stretching post,

Fig. 7 is a side elevation of the wire clamp,

Fig. 8 is a perspective view of the adjustable band to facilitate the securing of the bearing block in various distances within the post.

Like numerals of reference designate cor- 75 responding parts in all the figures of the drawings.

Referring to the drawings, the numeral 1 designates a supporting or stretching post and it is shown spaced laterally and at some 80 distance from the fence post designated B, upon which the wires C are to be stapled as at D.

The supporting standard or post comprises the spaced vertical side walls 2, which 85 have their lower ends converging as at 3 to define an insertion point 4, which facilitates the embedding of one end of the post or standard in the ground. The post is provided adjacent its lower end with a horizontal block 5 and laterally extending lugs 6 which are arranged on opposite sides thereof as shown in Fig. 5, the side walls 2 are provided adjacent their lower ends and centrally of the side edges thereof with 90 95 alined transverse openings 7, the purpose of which will be hereinafter more fully described.

The openings 7 are located adjacent the horizontal shoulder 5, as clearly shown in Fig. 5.

A cap 8 is secured to the upper open end 5 to the upper edges of the sides 2 of the standard or post 1. A bearing block 9 is slidably arranged between the sides 2 of the post 1 and is provided centrally with transverse screwthreaded openings 10, which are 10 adapted to extend parallel with the sides 2 as shown.

An adjusting or tightening band 11 is substantially rectangular in cross section and is slidably arranged over the sides 2 and 15 is provided in its front and rear walls with aligned openings 12, which are adapted to receive transversely therein, the exterior screwthreaded shaft 13. The shaft 13 is screwthreadedly fitted through the openings 20 12 of the adjusting band 11 and through the opening 10 in the bearing block 9, as clearly shown in Fig. 3. Crank handles 14 are screwthreadedly mounted in the sides of the adjusting band 11 at diametrically opposite 25 points and at right angles to the openings 12 and adapted to be threaded into engagement with the side walls 2 for urging the sides into engagement with the bearing block 9 for adjustably supporting the same in 30 various positions about the length of the side walls 2 of the supporting post 1, thus facilitating the locating of the shaft 13 in alignment with the ends of the wires C of the fence, thus it can be seen that either of the 35 wires C can be stretched to the desired position preparatory to the stapling of the same to the post B as shown in Fig. 1.

An operating wheel 15 is secured to the outer end of the shaft as at 16 to facilitate 40 the rotating of the shaft and moves the shaft inwardly or outwardly with relation to the bearing block 9 and adjusting band 11. The inner end of the shaft terminates into an eye 17, to which is connected one end of the 45 flexible chain 18.

A circular supporting plate 19 has formed on its periphery a swiveled connection 20, which is connected to the free end of the flexible chain 18. A pair of cam shaped 50 members 21 are eccentrically pivoted to one side face of the circular plate 19 and in close proximity to each other and are adapted to securely clamp the wires C between their opposing faces to facilitate the holding of the 55 wire when the shaft 13 is moved outwardly away from the post B so as to effectively stretch the wire preparatory and prior to the stapling of the same to the post B as shown.

60 A pair of reinforcing and bracing rods 22 are pivotally secured to the post 1 and adjusting band 11 respectively at one end and have their opposite ends terminating into circular post engaging members 23, which

post engaging members 23 are adapted to engage the post B and retain the post or standard 1 in spaced relation to the post B and hold the same against tilting during the stretching action of the wires. The lower brace 22 has its end bifurcated as at 24 to 65 provide the diverging arms, the terminals of which extend forwardly and parallel with one another, and are pivotally secured as at 70 25 to the inner sides of the members 2 through the medium of the openings 7 by 75 bolts 26, which extend through the openings 7 in the sides 2, and the parallel ends of the arms 27 of the lower brace 22 are located in close proximity to the horizontal block 5 so that when the same is in a horizontal position, it will rest upon the block 5, thus limiting the downward movement of the same, it being understood that when the device is not in use, it is only necessary to raise the brace upwardly and position the same 80 between the spaced sides 2 of the post 1. The upper brace 22 has one end bifurcated as at 28 and the terminals of the arms are pivotally secured as at 29 to the ears 30, which are formed on one side of the adjusting band 11 as shown in Figs. 2 and 8.

In operation, the point 4 of the post 1 is embedded in the ground and the lugs 6 engaging the surface of the ground limit the inward movement of the same, the cap facilitating the driving of the same in with a hammer, sledge or the like. The arms 22 are arranged in a horizontal position and are engaged against the post B as shown, the wires C have their ends arranged between the cams 21, the wheel 15 is rotated in a counter clockwise direction, thus moving the shaft outwardly through the screw threaded openings in the bearing 9 of the adjustable band 11, thus the wire is stretched and stapled as at 105 D to the post B, it being understood that it is only necessary to loosen the members 14 and adjust the bearing 9 upwardly or downwardly between the sides 2 to locate the inner end of the shaft 13 directly in alignment 110 with the ends of the wires C, thus tightening the members 14 and holding the bearing 9 in this position. When it is desired to release the wire after being stretched, it is only necessary to rotate the wheel in a clockwise direction, thus causing the flexible chain 115 to sag and the wire can be instantly released from the cams 21 carried by the plate 19.

What is claimed is:

In a wire stretcher, a supporting post 120 comprising spaced parallel side members connected adjacent their lower ends by an integral horizontal web, a band fitting about said post and adjustable longitudinally thereof, a block slidable between said side members, a screw shaft operable through said block and extending through the band, means for attaching one end of the screw

shaft to a wire to be stretched, a brace rod pivotally secured between said side members adjacent said web and so positioned as to engage the web and be supported thereby in 5 horizontal position when in its lowermost position, and a brace rod pivotally secured to said band and corresponding approximately in length to the first mentioned brace rod, the brace rod carried by the band being 10 movable about a horizontal axis so as to be

readily lowered into engagement with a fence post with which the first mentioned brace rod is engaged.

In testimony whereof I affix my signature in presence of two witnesses.

ALFRED JOHNSON.
